UNITED STATES PATENT OFFICE.

WILLIAM J. CARROLL, OF WEST HAVEN, CONNECTICUT, ASSIGNOR TO SARGENT & COMPANY, OF NEW HAVEN, CONNECTICUT.

PANIC BOLT LOCK.

Application filed January 9, 1923. Serial No. 611,685.

To all whom it may concern:

Be it known that I, WILLIAM J. CARROLL, a citizen of the United States, residing in the town of West Haven, county of New Haven, State of Connecticut, have invented certain new and useful Improvements in Panic Bolt Locks, of which the following is a full, clear, and exact description.

This invention relates to emergency exit locks or so-called panic bolt locks of the type which are applied to the doors of public buildings such as school houses, theaters, department stores, and the like, for facilitating exit when a panic results from a fire or other cause.

The invention has particular reference to a panic bolt mechanism in which the door is provided with a bolt to engage a keeper or strike plate upon the floor and arranged to be released from its keeper by means of a swinging bar or the like upon the inner face of the door. My improved panic bolt mechanism may be used upon a single door or it may be used upon double doors, as shown in the accompanying drawings, and in the latter case, it will usually be found expedient to use it in connection with the door which normally remains closed and to which the companion door is latched or locked.

It sometimes happens that when a panic occurs within a building and a number of persons crowd against the door in seeking an exit from the building, that the lock or latch bolt is so firmly bound by friction in its keeper, due to the immense pressure upon the door, that it cannot be withdrawn by the usual emergency or panic bar, and as a result, the door will not open. The present invention is designed to avoid such a condition, and while it is provided with a latch structure which is permitted to swing out of the way or roll back upon the opening movement of the door, there is also provided a sliding bolt to control this latch member, but so arranged that it can never bind within its keeper.

One of the objects of my invention is to provide an emergency exit mechanism of the character described, such that there will be no danger of the mechanism jamming or binding when pressure is applied to the inner face of the door as is sometimes true in the case of a panic.

Another object of my invention is the provision of a sliding bolt which acts to effect the retention of the door in closed position with associated mechanism which will prevent any binding or jamming of the bolt within its keeper.

A still further object of my invention is the provision of a protruding bolt to effect the retention of the door in closed position, and associated mechanism whereby the door is prevented from an opening movement until the bolt is clear of its keeper, so that there will be no tendency for the bolt to bind frictionally against the edge of the keeper opening.

Another object of my invention is to provide upon the upper or lower edge of the door a latching or locking mechanism which will be retracted by an opening pressure upon the door, and mechanism to control the latch devised to hold it in operative locking position when desired.

More specifically, I provided the door at its upper and lower edge with a pivoted latch mechanism designed to be moved to inoperative position when an opening movement is imparted to the door, and arranged upon the door a sliding bolt to control the operation of the latch device, the arrangement being such that an opening movement of the door may not be begun until after the sliding bolt is free from the mechanism with which it cooperates.

In the accompanying drawings:

Fig. 1 is an inside elevational view of a door provided with a panic bolt mechanism embodying my improvements;

Fig. 2 is a sectional view on line 2—2 of Fig. 1;

Fig. 3 is an enlarged detail view of the mechanism shown in the lower part of Fig. 2;

Fig. 4 is a view similar to Fig. 2, but showing the parts in another position;

Fig. 5 is a sectional view on line 5—5 of Fig. 3;

Fig. 6 is a sectional view on line 6—6 of Fig. 5;

Fig. 7 is a sectional view on line 7—7 of Fig. 4; and

Fig. 8 is a sectional view on line 8—8 of Fig. 4.

In the preferred embodiment of my invention which I have chosen to illustrate in

the drawings, a pair of doors of the usual type are shown at 10, one of these doors being provided with bolt operating rods 11 and 12 extending from a casing 13 at an intermediate part of the door to the upper and lower edges. Upon the casing 13 is pivoted an emergency or panic bar 14, provided with a finger 15, extending within the casing and between operating slides 16 and 17, which are connected to the rods 11 and 12 respectively. The mechanism within the casing to effect the operation of the rods 11 and 12 from the panic bar 14 may be of any desired type, the form shown, however, being that shown in the patent to Voight, No. 1,345,041, June 29, 1920. It will be understood, however, that any desired kind of operating mechanism for these rods may be used without departing from the present invention.

On the lower edge of the door is provided a keeper plate 18 having a keeper opening 19 therein, and within the sill or threshold is countersunk a casing 20 provided with supporting lugs 21 and 22. Through these lugs is passed a pivot pin 23 and upon this pin is pivoted a latch member 24 adapted to swing upwardly through an opening 24^a in the face plate of the casing 20 and enter the keeper opening 19 and hold the door in closed position. Cooperating with the latch member 24 is a lever 25 pivoted at 26 to the lugs 21 and 22, the forward end portion of this lever being in the form of a finger 26^a which rests within a recess 27 formed in the latch member 24.

A stirrup 28 is pivotally mounted upon the pivot pin 23 and is provided with an intermediate portion 29 which overlies the end 30 of the lever 25, and is provided with an upstanding boss 31 which is designed to close an opening 32 in the face plate of the casing 20. The spring 33 is provided to normally urge the stirrup member 28 upwardly so that the boss 31 will close the opening 32.

In order to control the movement of the latch member 24 and to throw it positively into position to hold the door closed, when this is desirable, I have provided upon the lower portion of the inside face of the door a casing 34 containing mechanism controlling the rod 11 by means of the panic bar, through which in turn the latch member 24 is controlled. This mechanism consists of a bolt or plunger 35 slidably mounted in the casing 34 and adapted to be protracted through the opening 32 to contact with the boss 31 on the stirrup 28, and thus force the stirrup downwardly, and by means of the lever 25, throw the latch member 24 into its protracted position within the keeper opening 19. This position of the parts is shown in Figs. 2 and 3 and it will be apparent that as long as this condition ob-

tains, it will be impossible to open the door due to the retention of the door by the latch 24. It will also be observed that the opening 32 is somewhat larger in diameter than the protecting end of the plunger 35, so that as long as the door is held by the latch 24, the plunger bolt 35 will have no frictional contact with the periphery of the opening 32.

The bolt 35 is controlled by means of the rod 11 and panic bar 14 and for this purpose, the upper portion of this bolt is provided with a notch 36 adapted to receive the finger 37 upon the lower end of the rod 11. It will be noted that the notch 36 is somewhat wider than the finger 37 so that there will be a slight amount of lost motion between these parts for a purpose to be hereinafter explained.

The normal position of the parts is that shown in Figures 2 and 3, and it will be noted by reference to Patent No. 1,345,041, previously referred to, that a movement of the panic bar in either direction will tend to pull the rod 11 upwardly and withdraw the bolt 35 from its operative protracted position. It will be obvious that it might be possible for the bolt 35 to be retracted by pressure upon the door in an opening direction, on account of the tendency of such pressure to swing the latch 24 about its pivot 23. To guard against such a contingency, a detent or stop is arranged in the form of a stirrup 38 which is pivoted at 39 within the casing 34 and is urged by a spring 40 into operative position to dog the bolt 35 in the position shown in Fig. 3. The lower edge of this detent is adapted, when the bolt is in this position, to drop behind a shoulder 41 formed on the bolt so as to effectually dog the latter in protracted position. It will be apparent that, regardless of the amount of pressure which may be applied in an upward direction to the lower end of the bolt 35, it cannot be retracted into the case 34 until the detent 38 has been swung to an inoperative position.

While it is essential that the bolt be effectually and firmly dogged against retraction by pressure upon its lower end, it is just as essential that it be easily retracted by a pull upon the rod 11. Such an operation is obtained by providing the lower portion of the finger 37 with a bevelled or cam face 42 which is adapted to engage the complementary face 43 of a cross bar 44 upon the stirrup. It will be apparent, when a pull is exerted upon the rod 11 that, due to the lost motion connection between the finger 37 and the recess or slot 36, the lower end of the rod 11, by means of its cam 42 engaging the cam 43, will first swing the detent upwardly out of engagement with the shoulder 41 and then a

continued movement of the rod 11 will effect retraction of the bolt 35. The lost motion connection between the rod 11 and the bolt 35 enables this rod to throw the detent out of engaging condition prior to the exertion of any pulling force upon the bolt. The operation of my improved locking device is as follows:

When the door is opened, the latch 24, 10 the lever 25, and stirrup 28 assume the positions shown in Fig. 4 wherein the latch rests in a lower position below the face plate of the casing 20. The door is then free to swing to a closed position without interference on the part of the latch member, 15 as also shown in Fig. 4. When the door reaches this position, the bolt 35 drops into the opening 32 and by impinging upon the boss 31 forces the latch 24 upwardly into the keeper opening 19 and holds the door in 20 closed position. The detent 38 immediately drops behind the shoulder 41 so that any pressure upon the main part of the door will not effect the opening thereof. It will 25 be obvious from Figures 2 and 3 that as long as the latch member 24 engages the inner face of the keeper opening, the bolt 35 will not be permitted to impinge against the periphery of the opening 32, and hence, 30 there will be no danger of the bolt jamming or binding if pressure is exerted on the inside of the door in case of a panic, so as to render it difficult or impossible to withdraw the bolt. However, in view of the fact 35 that the bolt 35 is entirely free from engagement with the sides of the opening when a light pressure is applied to the panic bar 14, the bolt is easily and quickly withdrawn and thus the latch member 24 is permitted 40 to drop back into the casing 20, due to its own weight, or if it is inclined to stick, it will be positively moved within the casing by an opening pressure applied to the door. It will be apparent, therefore, that if pressure 45 is applied to the panic bar in a direction to push the door open, that such a pressure will withdraw the bolt 35 and immediately thereafter effect the opening of the door.

While I have shown and described a 50 preferred embodiment of my invention, it will be understood that I do not limit myself to all the details shown but on the other hand, the parts are capable of modification and variation within the spirit of the invention and within the scope of the appended claims.

What I claim is:

1. Door holding mechanism comprising a 55 latch bolt adapted to be mounted in the door jamb and to enter a keeper opening in the door; a second bolt mounted upon the door and controlling said latch bolt, said latch bolt holding said door in position to prevent the binding of said second bolt 60 against the door jamb.

2. Door holding mechanism comprising a latch bolt and a keeper, said latch bolt being mounted in the door jamb and the keeper being carried by the door; said bolt being moved to retracted position by an 70 opening movement of the door, a second bolt mounted upon the door and protractable to control the latch bolt and manually operable means to operate said second bolt, said latch bolt holding the door closed until 75 said manually controlled bolt has been withdrawn from operative position.

3. In a door holding mechanism, a latch bolt pivotally mounted in the door jamb, adapted to enter a keeper opening in the 80 door; and pivoted to swing to retracted position in the same direction as that of the door to open position, a second bolt mounted upon the door and operable to cause the projection of said latch bolt into the keeper opening. 85

4. In a door holding mechanism, a bolt movably mounted in the door jamb, adapted to be projected in a keeper opening in the door, said bolt being moved to retracted position by an opening movement of the 90 door; and a second bolt mounted upon the door and movable to effect the projection of said latch bolt.

5. In a door holding mechanism, a latch bolt movably mounted in the door jamb and adapted to be projected into a keeper opening in the door; said bolt being moved to retracted position by an opening movement of the door; a lever having a part 95 thereof engaging said bolt; a second bolt 100 mounted upon the door and movable to cause the actuation of said lever to project the latch bolt into the keeper opening.

6. In a door holding mechanism, a latch bolt movably mounted in the door jamb, adapted to be projected into a keeper opening in the door; and pivoted on an axis in the plane of the door when the latter is in closed position; a second bolt movably mounted upon the door and means to transmit the motion of said second bolt to said latch bolt to project the latter into the keeper opening. 105

7. In a door holding mechanism, a door 110 provided with a keeper opening in the lower edge thereof, a latch bolt pivoted below the door and adapted to swing upwardly into said opening, a lever mounted adjacent said bolt and having one end engaged therewith, a controlling bolt movably mounted upon the door and engaging the other end of said lever to actuate said pivoted bolt. 115

8. In a latching mechanism for a door, provided with a keeper opening in the lower edge thereof, a case mounted in the threshold 120 below said door, a bolt pivoted to said casing and adapted to swing upwardly into the keeper opening, a lever mounted in the casing and having one end engaged with said bolt, said lever having a 125 130

part thereof extending adjacent an opening in the upper side of the casing, and a controlling bolt mounted upon the door and projectable into said opening to actuate 5 said lever to move said pivoted bolt.

9. In a latching mechanism for a door, having a keeper opening in the bottom edge thereof, a casing mounted in the threshold below the door and provided with two openings, a bolt mounted in the casing and adapted to be projected through one of said openings into the keeper opening in the door, a controlling bolt mounted on the door and adapted to be projected into the 10 casing through the other opening, and means to cause the actuation of said first named bolt by the movement of said controlling bolt including a lever pivoted between its ends, having one end engaging 15 said first named bolt and its other end positioned adjacent one of the two openings in the casing, and a stirrup engaging the last named end of the lever and being in turn engaged by said controlling bolt.

20 10. In a door holding mechanism, a latch bolt movably mounted in the door jamb and adapted to enter a keeper opening in the door; a second bolt movably mounted upon the door and adapted to be protracted into 25 an opening in the door jamb and means mounted within the jamb to transmit the motion of said second bolt to said first bolt, said latch bolt holding said door in position to prevent the binding of said second bolt 30 against the edge of the jamb opening.

11. In a door holding mechanism, a latch bolt movably mounted in the door jamb and adapted to be projected into a keeper opening in the door; a second bolt mounted upon the door and adapted to be projected into an opening in the jamb to actuate said latch bolt, said latch bolt holding said door in position to prevent the binding of said second bolt 40 against the edge of the jamb opening.

45 12. In a door holding mechanism, means to hold the door in closed position, a controlling bolt projectable into an opening in the jamb to control said means, said means holding the door in position to prevent binding of said controlling bolt against the edge of the jamb opening until said bolt has been withdrawn.

50 13. In a door holding mechanism, a bolt mounted in the threshold below the door and adapted to be swung into engagement with the door to hold the latter in closed position, a controlling bolt for said first named bolt, a casing mounted on the door 55 in which said controlling bolt is slidably mounted, an operating rod mounted on the door having a lost motion connection with said controlling bolt, a dogging member pivoted to the casing and adapted to hold 60 the controlling bolt in protracted position,

and means whereby the actuation of said rod will move the dogging means to inoperative position.

14. In a door holding mechanism, a casing mounted on the door, a bolt reciprocably mounted in the casing, an operating rod reciprocably mounted in the casing in alignment with said bolt, dogging means pivoted to the casing and normally urged into engagement with said bolt to hold it in protracted position, and means whereby the actuation of said operating rod will move said dogging means to inoperative position. 75

15. In a door holding mechanism, a casing adapted to be mounted on a door, a bolt reciprocably mounted in the casing and provided with a notch therein, an operating rod reciprocably mounted on the casing and having a finger loosely received in said notch to provide a lost motion connection between the rod and bolt, a stirrup pivoted to the casing and adapted to engage the bolt to dog it in protracted position, and cooperating cam surfaces on said stirrup and operating rod whereby the actuation of the latter will move said stirrup into position to disengage the bolt prior to the retraction thereof. 85

16. In a door holding mechanism, a latch bolt mounted in the threshold of a door and adapted to be protracted into an opening in the lower edge of the door; a controlling bolt mounted upon the door and adapted to be protracted into an opening in the threshold to actuate the latch bolt, said latch bolt holding said door in position to prevent the binding of said controlling bolt against the edge of the threshold opening. 95

17. In a door holding mechanism, a bolt mounted in the door jamb, adapted to be protracted into a keeper opening in the door, and urged to retracted position by an opening movement of the door; a second bolt mounted upon the door and adapted to control said first bolt, and means to dog 105 said first bolt in operative position.

18. In a door holding mechanism, a bolt mounted in the door jamb, adapted to be protracted into a keeper opening in the door, and urged to retracted position by an opening movement of the door; a second bolt mounted upon the door and adapted to control said first bolt, and means to prevent 115 retraction of the first bolt by pressure applied to the door. 120

19. In a door holding mechanism, a bolt mounted in the door jamb, adapted to be protracted into a keeper opening in the door, and urged to retracted position by an opening movement of the door, a second bolt mounted upon the door and adapted to control said first bolt, and means to dog 125 said second bolt to prevent the retraction of it and said first bolt by pressure applied to the door. 130

20. In a door holding mechanism, a latch bolt pivoted in the door jamb, adapted to swing into a keeper opening in the door, and urged to retracted position by an opening movement of the door, means movably mounted upon the door adapted to hold said pivoted bolt in protracted operative position, and dogging means for said movably mounted means to prevent the retraction of 5 said pivotally mounted bolt by pressure applied to the door.

21. In a door holding mechanism, a casing, a two-part bolt therein, dogging means on the casing for one of the parts and means 15 whereby actuation of the other part will move the dogging means to inoperative position.

22. In a door holding mechanism, a casing, a two-part bolt therein, means pivotally carried by the casing to dog one of the parts of said bolt against movement in one direction, and means whereby a movement 20 of the other part of the bolt in that direction will release said dogging means.

23. In a door holding mechanism, a casing, a two-part bolt, both parts of which are mounted to reciprocate in the casing, dogging means for said bolt whereby a pressure applied to one end thereof will be ineffective 25 to move said bolt, but a pull upon the other end of said bolt will move the latter.

24. In a door holding mechanism, a two-part bolt, said parts being in alignment and having a lost motion connection therebetween, dogging means for one of said parts and means whereby movement of the other 30

part will release the first part from said dogging means.

25. In a door holding mechanism, a two-part reciprocating bolt, a lost motion connection between said parts whereby movement of one will cause a movement of the other in either direction, dogging means for one of said parts, and means whereby a movement of the other part first releases 40 the dogging means and then moves said first part.

26. In a panic bolt mechanism for a swinging door, provided with a strike opening in the lower edge thereof, a bolt mounted in the floor below the door and adapted to be projected into said opening, a controlling bolt for said projectable bolt reciprocably mounted on the door, an operating rod for said controlling bolt, dogging means for 50 the controlling bolt, and means upon said operating rod for moving the dogging means to inoperative position.

27. In a panic bolt structure, a retaining bolt adapted to be mounted below the door 60 and projected into a strike opening in the lower edge thereof, a two-part controlling bolt for said retaining bolt, means to dog one of the parts of said bolt against movement in one direction and co-operating 65 cam means upon said dogging means and the other part of the bolt whereby said dogging means is moved to inoperative position.

In witness whereof, I have hereunto set 70 my hand on this 3 day of January, 1923.

WILLIAM J. CARROLL.
